UNITED STATES PATENT OFFICE.

BENJAMIN W. MORGAN, OF ATLANTA, GEORGIA, ASSIGNOR TO SIMPLEX PRESS COMPANY,
OF ATLANTA, GEORGIA, A CORPORATION OF GEORGIA.

PRINTING-PRESS.

No. 858,743.

Specification of Letters Patent.

Patented July 2, 1907.

Application filed January 12, 1905. Serial No. 240,747.

To all whom it may concern:

Be it known that I, BENJAMIN W. MORGAN, a citizen of the United States, residing at Atlanta, in the county of Fulton and State of Georgia, have invented a new and useful Printing-Press, of which the following is a specification.

This invention relates to that class of printing presses having a bed and a cylinder coacting therewith. The object is to provide a novel press wherein the elements 10 and combination of elements are extremely simple and the necessary cycle of operations is effectively produced, and properly maintained, the simplicity of the structure making the cost of manufacture comparatively small and reducing to a very material degree the chances 15 of imperfections, both in construction and operation.

The embodiment of the invention which is at present considered preferable is illustrated in the accompanying drawings.

Figure 1 is a view in elevation of one side of the machine. Fig. 2 is a similar view of the opposite side of the machine. Fig. 3 is a vertical longitudinal sectional view. Fig. 4 is a detail cross sectional view through the operating means for the bed. Fig. 5 is a detail sectional view of the clutch member of the cylinder rotating means. Fig. 6 is a detail perspective view of one of the gages and a portion of the paper-clamping device. Fig. 7 is a detail view showing the combined operating means for the paper-clamping device. Fig. 8 is a rear elevation of the cylinder and paper-operating mechanism 25 coacting therewith. Fig. 9 is a sectional view showing the fly-frame actuating mechanism. Fig. 10 is a cross sectional view showing the driving and counter shafts and the various devices carried by the latter. Fig. 11 is a plan view of the actuating mechanism for 30 the cylinder elevating and lowering means. Fig. 12 is a detail sectional view taken on the line 12-12 of Fig. 11. Fig. 13 is a detail sectional view taken on the line 13-13 of Fig. 5.

Similar reference numerals designate corresponding 40 parts in all the figures of the drawings.

In the embodiment illustrated, a suitable supporting frame 8 is employed, in the upper portion of which is mounted a horizontal longitudinally reciprocating bed 9, carried upon rollers 10. This bed is provided on its 45 under side with a longitudinally disposed rack 11 and located beneath the same is a longitudinal bar 12, constituting, in effect, a part of the supporting frame. The bar 12 has a portion between its ends divided, as shown at 13, to form spaced tracks, the upper edges of which 50 have racks 14. A gear wheel 15 of comparatively large diameter meshes with the rack 11 of the bed and extends between the tracks 13. On the opposite sides of and secured to the gear wheel 15 are other gear wheels 16 of less diameter than the same and engaging the

racks 14. It will, therefore, be evident that if these gears are reciprocated, the travel of the smaller gear wheels will be comparatively small, while the larger gear wheels will cause the bed to move a relatively great distance. The means effecting the movement of the gear wheels, and consequently of the bed, is as follows:

A driving shaft 17 is mounted transversely in the frame and carries a balance or fly-wheel 18. This shaft may be operated by any suitable power, as will be clearly apparent, but, in the present instance, the press is to be run by hand, and therefore, a handle 19 is shown, attached to said balance wheel. The driving shaft 17 carries a pinion 20, meshing with a large gear 21, secured to a counter shaft 22, also journaled transversely in the frame. The gear wheel 21 constitutes, furthermore, a crank wheel, one of the spokes thereof carrying a crank pin 23, that can be secured in any of a line of openings 24, formed in said spoke. To the crank pin 23 is pivotally secured a pitman rod 25, which rod is connected to the common axle 26 of the gear wheels 15 and 16. Thus, it will be seen that, when motion is imparted to the main driving shaft 17, the gear and crank wheel 21 will be revolved, thereby reciprocating the gear wheels 15 and 16 and effecting the reciprocation of the bed. Moreover, it will be noted that the bed will operate slowly as it reaches the ends of its movement, so that the shock of the reversal of such movement will be reduced to a minimum.

Coacting with the bed and located over the same is a rotatable cylinder 27, journaled in the upper ends 85 of vertical standards, each comprising sections 28 and 29. The upper sections 28 are provided with enlargements 30, constituting bearings for gudgeons 31 of the cylinder, while the lower sections 29 are provided with enlargements 32, in which are journaled cams 33, 90 carried by a rock shaft 34, journaled transversely in the supporting frame 10. The sections are connected at their adjacent ends by adjusting screws 35, threaded into said sections and having jam nuts 36, adapted to bear against the ends of the same to prevent the accidental turning of the screws. The vertical movement of the cylinder is secured by the operation of the rock shaft and its operation is accomplished from the driving mechanism of the bed. A link 37, located just inside the frame, has a pivotal crank connection 38 with the rock shaft 34 by means of a disk 39, adjustably secured to said rock shaft. The link 37 has its outer end provided with a head 37^a, having a longitudinal slot 37^b, that receives the counter shaft 22, said slot thus permitting the longitudinal sliding 100 movement of the link. The head is provided on opposite sides of the slot with projections 37^c, the rear faces of which are inclined, the front faces being pref-

erably flat and at right angles to the adjacent faces of the head. These projections are disposed in the path of movement of a pin 40, carried by a disk 41, adjustably secured on the counter shaft by means of a set screw 42, the head 37^a being urged towards said disk by means of a coiled spring 43, interposed between the head and the adjacent side of the frame. It will thus be apparent that, during the reciprocation of the bed, the revolution of the crank disk 41 will cause this crank pin 40 to alternately engage the opposite square shoulders of the projections 37^a, thereby moving the link in opposite directions, consequently, moving the rock shaft and elevating and depressing the cylinder. The movement of the cylinder is, of course, timed to the action of the bed, so that when said bed is moving in one direction, the cylinder is depressed, and in coacting relation with the same, and when moving in an opposite direction, said cylinder is elevated so as to be entirely free of such bed.

20 If a reverse movement of the mechanism should take place, the pin 40 will successively ride over the inclined sides of the projections, and thus forcing the head 37^a away from the disk and against the tension of the coiled spring 43 will not effect the movement 25 of the link and all danger of injury or breakage to the parts will be avoided. The throw-off movement of the cylinder can also be accomplished at any time through the medium of a foot treadle lever 40^a, pivoted at one end to the frame and having a link connection 30 41^a with an arm 42^a, that is attached to the rock shaft 34.

In order to secure an initial rotation of the cylinder prior to its operation over the forms on the bed, said cylinder is driven directly from the driving mechanism so that a rotary movement of the same is secured 35 independently of the bed. As shown in Figs. 1, 5 and 13, the main or drive shaft 17 carries at its outer end, and preferably just inside the balance wheel 18, a pulley 44, which pulley has a clutch connection with the shaft through said balance wheel. To this end, the 40 said wheel is provided in the face adjacent to the balance wheel with a recess 45, having an inclined bottom and terminating at one end in an abrupt shoulder. In a socket in the hub of the fly-wheel is slidably mounted a pin 46, yieldingly urged outwardly against 45 the pulley 44 by means of a spring 47, located behind said pin. This pin is arranged to engage in the recess 45 and thus turn the pulley 44. A belt 48, passing about the pulley 44, also extends around a pulley 49, secured to one of the gudgeons 31 of the cylinder.

50 The speed of rotation given to the cylinder by the belt and pulley connection with the driving shaft is synchronous with the motion of the bed when the type engages said cylinder. The purpose of this belt drive is to secure the movement of the cylinder independently of the bed, so that the paper may be carried and fed around to the proper position to take the forms without the necessity of cushions or bearings in advance of the forms to effect a preliminary rotation of the cylinder.

55 30 In operation, the pulley 44, being actuated by the drive shaft 17, revolves the cylinder with a steady continuous motion until the forms reach the cylinder on the impression stroke, whereupon the movement of the cylinder is accelerated synchronously with the 60 motion of the bed, the pulley of the cylinder there-

upon driving the pulley of the main shaft and causing it to overrun the motion of said main shaft. This overrunning is permitted by the pin clutch between the fly wheel and the adjacent pulley. Said pulley being now operated at a greater rate than the fly wheel, the pin will ride up the inclined bottom of the recess 45 and will frictionally bear against the adjacent face of the pulley. When the forms leave the cylinder, said cylinder stops momentarily or until the pin carried by the hub reaches the recess, and, riding down in said recess, abuts against the terminal shoulder thereof, whereupon the normal motion is again imparted to the pulley, and consequently to the cylinder.

The means for feeding the paper to the cylinder is as follows: An inclined feed table 50 is mounted upon the frame 8 above the bed, and has its lower end disposed directly over the cylinder. In spaced relation to said lower end are located the upper ends of guide strips 51, extending in rear of and beneath the cylinder, and preferably slightly spaced from the same. These guide strips are secured to collars 52, which, in turn, are supported on a rock shaft 53, the rock shaft having a rotary movement in said collars. The lower ends of the guide strips are rigidly attached to a cross bar 54, secured beneath the cylinder, as shown in Fig. 90. The upper ends of the strips 51 are preferably upturned, as shown in Fig. 6, and have a bearing 55 for gages, each consisting of a pivot portion 56, journaled in said bearing and having at one end a downturned stop finger 57, movable into and out of coaction with the cylinder. The opposite end of the pivot portion is provided with a crank 58, that extends outwardly and beneath an arm 59, rigidly affixed to the rock shaft 53, by means of a set screw 60, which permits the adjustment of said arm on the rock shaft. The free ends of the arms 59 (one being located at each end of the rock shaft 53) carry a paper-clamping device in the form of a roller 61, journaled to and between said arms and movable into and out of coaction with the cylinder when the arms are swung. This roller is grooved spirally, so that it spreads wrinkles out of the paper passing thereunder. A bell crank lever 62 is journaled on one side of the frame and one arm thereof has a link connection 63 with one of the arms 59. The other or horizontal arm of the bell crank lever 62 extends over a cam 64, mounted on the counter shaft 22, and has a pivoted dog 64^a, that rides upon the active or peripheral surface of said cam. A weight 65 may also be adjustably mounted on this arm of the lever in order to secure the proper action of the parts, as hereinafter described.

The operation of the feeding means, above described, may be briefly outlined as follows: During the movements of the bed and cylinder, the cam 64 is, of course, rotated. Consequently, at predetermined intervals, the horizontal arm of the bell crank lever is raised by said cam and the arms 59 are thus swung upwardly, so that the roller 61 is carried away from the cylinder. As the stop fingers 57 of the gages are heavier than the cranks, it will therefore be evident that said stop fingers will drop into coaction with the cylinder and lightly rest against the same. Consequently, if paper is now fed from the table 50, it will pass freely under the roller 61 and abut against the stop fingers of the gages. As the movement of the cam continues, the

dog '64^a of the horizontal arm of the bell crank lever will reach the inner part of said cam so as to permit the arm to drop. The result is that the clamping roller 61 will move downwardly into coaction with the cylinder, clamping the paper thereon, so that the rotation of said cylinder will cause the paper to be fed downwardly and properly to the forms of the bed. The downward movement of the arms 59 will cause a simultaneous movement on the part of the crank 58 of the gages, so that the stop finger will be raised to permit the free passage of the paper therebeneath. It will, of course, be understood that these movements are also properly timed with respect to the operation of the bed and cylinder.

15 The delivery mechanism will now be described: Located beneath the feed table 50 and above the path of movement of the bed 9 are sets of upper and lower endless tapes 66 and 67. The upper of these tapes, designated 66, pass around the cylinder 27 and are driven thereby, while they also run around a roller 68, located beneath the upper end of the table. The lower tapes 67 of the sets pass about rollers 69 and 70, the rear roller 70 being disposed directly adjacent to the cylinder 27, and just in advance of the lower guide 25 strips 51. This roller 70 has attached to it a pulley 71, located at one side of the machine and in engagement with the driving belt 48 of the cylinder. Consequently, it will be apparent that these tapes all move synchronously with the cylinder at all times and without regard 30 to the variableness of the speed of its rotation.

At one end of the frame and directly beneath the delivery portions of the tapes 66 and 67 is journaled a fly-frame that ordinarily maintains an upright position. This fly-frame consists of a rock shaft or bar 72, having 35 the usual fingers 73, the upper ends of which are located contiguous to the tapes 67. The rock bar 72 has a bracket 74, to which is pivoted the lower end of a link 75, the upper end of said link being pivotally connected to another link 76, swingingly suspended from 40 its upper end and having attached to its lower end a spring 77, said spring being connected to the rock bar 72, through the medium of an ear 78, carried, by said bar. A roller 79, journaled upon the suspended link 76, rides upon the periphery of a cam 80, which cam is 45 carried by the counter shaft 22 and is constructed so that, during the greater part of its rotation, the fly-frame will be held in elevated position against the tension of the spring 77; but, at a certain point in its travel, the roller 79 is permitted to move inwardly 50 toward the shaft, thus allowing the spring 77 to operate and swing the fly-frame downwardly, as shown in Fig. 9. This movement is, of course, timed to the other mechanism, so that the operation of the fly-frame will take place just as a printed sheet is delivered from the 55 tapes.

Inking mechanism, operated in a peculiar manner by certain of the elements already described, is also employed. As shown, this inking mechanism comprises spaced inking rolls 81, over and in engagement 30 with which is located a distributing roll 82. A fountain 83 of any desired construction is provided with a feed roll 84, and a transmitting roll 85 operates between the feed roll 84 and the distributing roll 82. The said feed roll is given a step by step movement, and for this

purpose, at one end of the same is secured a ratchet 65 wheel 86, engaged by a dog 87 carried by an oscillating lever 88. To the lever is connected a link 89, that is also pivotally connected to the link 37, already described. This link 37 has a longitudinal reciprocatory motion, and consequently the link 89 will be given a similar movement. The lever 87 is thus oscillated and the dog successively engaging the teeth of the ratchet wheel 86, will move the same. The transmitting roller 85 is journaled in arms 90, which are pivoted to the arms 59. As the arms 59 have a swinging movement, 75 it will be apparent that the transmitting roller will be moved from the feeding roll 84 to the distributing roll 82.

Assuming the press driven by any suitable power, it will be evident that when the bed reaches the limit of its movement in one direction, the cylinder will be 80 elevated and simultaneously with this elevation, the clamping roll 61 will be moved away from said cylinder while the gages will, as a consequence, drop into coaction therewith. Paper is thereupon fed beneath the clamping roll 61 and against the gages. As the bed 85 moves to the opposite limit of its movement, the clamping roll is depressed, the gages are elevated, and the paper is thereupon fed downwardly, so that it will be in proper position to pass beneath the cylinder as the form returns and said cylinder is depressed to printing 90 position. As said cylinder takes the form, it will also take the faster motion thereof, and the paper will be delivered by the guides between the coacting stretches of the tapes 66 and 67. These tapes will deliver it over the fly, which, at the proper instant, is operated to remove the sheet from the machine. Simultaneously with the elevation and depression of the cylinder is the action of the feed roll of the inking fountain, and simultaneously with the movement of the clamping roll 61 is the movement of the transmitting roll 85 of the 100 inking mechanism. It will be apparent that the mechanism employed for securing this cycle of operations is comparatively simple and that said elements may be properly adjusted so that the proper co-operation can at all times be secured.

From the foregoing it is thought that the construction, operation, and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described my invention what I claim as new and desire to secure by Letters Patent is:

1. In a printing press, the combination with a frame, of a cylinder mounted thereon, a reciprocatory bed also mounted on the frame and having a rack, a single bar located longitudinally of the frame beneath the bed and having its ends secured thereto, said bar having a portion between said secured ends divided and provided with spaced racks, a gear wheel located in the divided portion of the bar between the spaced racks and meshing with the bed rack, other gears secured to said wheel and meshing with the bar racks, and means for reciprocating the gears.

2. In a printing press, the combination with a bed, of a cylinder movable toward and from the bed, driving mechanism including a shaft, means for raising and lowering the cylinder, actuating means therefor including a reciprocatory device having a portion slidably mounted on the

- shaft, and a crank member carried by said shaft and movably engaging the device to effect its movement in opposite directions.
3. In a printing press, the combination with a bed, of a cylinder movable toward and from the bed, a cam for effecting the elevation of the cylinder, driving mechanism including a rotatable crank member, a link having a connection with the cam, and a device carried by the crank member and detachably engaging with the link during a portion of the revolution of said crank member.
4. In a printing press, the combination with a bed, of a cylinder movable toward and from the bed, a cam for effecting the elevation of the cylinder, driving mechanism including a crank member, a reciprocatory link having a connection at one end with the cam and a device carried by the crank member and automatically moving into and out of engagement with the link to move the same on the movement of the crank member.
5. In a printing press, the combination with a bed, of a cylinder movable toward and from the bed, a cam for effecting the elevation of the cylinder, driving mechanism including a rotary device having a crank pin, and a link having a pivotal connection with the cylinder elevating cam and furthermore, having an element disposed in the path of movement of the crank pin and automatically engaged thereby and disengaged therefrom during the rotation of the device.
6. In a printing press, the combination with a bed, of a cylinder movable toward and from the bed, means for moving the cylinder, driving mechanism including a rotatable crank member provided with an outstanding element, and a link having a connection with the cylinder moving means, said link being provided with an offset element that is automatically engaged by and disengaged from the element of the crank member during the rotation of said member.
7. In a printing press, the combination with a bed, of a cylinder movable toward and from the bed, means for thus moving the cylinder, driving mechanism including a shaft having a crank member, and a link connected to the cylinder moving means and having a head that surrounds the shaft and is slidable thereon, said head having a portion detachably engaged by the crank member of the driving mechanism during the movement thereof.
8. In a printing press, the combination with a bed, of a cylinder movable toward and from the bed, means for moving the cylinder, driving mechanism including a shaft, a link having a connection with the cylinder moving means and provided with a head that surrounds the shaft, said head having abutments located on opposite sides of the shaft, and a crank member carried by the shaft and having a pin that engages the abutments for moving the link in opposite directions.
9. In a printing press, the combination with a reciprocating bed, of a cylinder mounted thereover and movable toward and from the bed, cam mechanism for elevating and lowering the cylinder, driving mechanism for reciprocating the bed including a shaft having a crank element, said crank element being provided with a crank pin, and a link connected to the cam mechanism of the cylinder elevating means and having a head that surrounds the shaft of the driving mechanism, said head being provided on its inner side with spaced abutments engaged by the crank pin.
10. In a printing press, the combination with a bed, of a cylinder movable toward and from the bed, and means for thus moving the cylinder, said means including a rotary crank members, and a device having connections with the cylinder, said device having portions located in substantially diametrically opposite portions of the path of movement of the crank member and detachably and successively engaged by the same during its rotation to move said device in opposite directions, said crank element being disengaged from both elements during portions of its revolution to permit the raising of the cylinder independently of its operation by the crank member.
11. In a printing press, the combination with a bed, of a cylinder movable toward and from the bed, and means for thus moving the cylinder, said means including a shaft, a rotary crank member mounted on the shaft, and a device having connections with the cylinder, said device having portions located in substantially diametrically opposite portions of the path of movement of the crank member and detachably and successively engaged by the same during its rotation to move said device in opposite directions, said crank element being disengaged from both elements during portions of its revolution to permit the raising of the cylinder independently of its operation by the crank member.
12. In a printing press, the combination with a movable bed, of a cylinder movable toward and from the bed, driving means for moving the bed, means for periodically elevating the cylinder, said means including devices that automatically and periodically engage and disengage upon the movement of the bed, and means for independently elevating the cylinder when the devices are disengaged.
13. In a printing press, the combination with a bed, of a cylinder movable toward and from the bed, a rock shaft having an eccentric connection with the cylinder, means for moving the bed, detachable connections between the said moving means and shaft for intermittently rocking the latter, and means connected to the shaft for independently operating the same when detached from said moving means.
14. In a printing press, the combination with a bed, of a cylinder movable toward and from the bed, a rock shaft having an eccentric connection with the cylinder for moving the same toward and from the bed, driving means for moving the bed, devices connected respectively to the driving means and shaft for periodically moving the latter, one of said devices automatically engaging and disengaging from the other, and a foot treadle connected to the shaft for independently operating the same when the devices are disengaged.
15. In a printing press, the combination with a reciprocating bed, of means for driving the same including a shaft, a cylinder coacting with the bed, a pulley loosely mounted on the shaft of the driving mechanism, a clutch connection between the pulley and shaft that permits the rotation of the pulley at a speed greater than that of the shaft and a belt connection between the clutch pulley and the cylinder.
16. In a printing press, the combination with a reciprocating bed having a rack, of a stationary rack, gearing engaging the racks, driving mechanism for reciprocating the gearings, said driving mechanism including a shaft, a rotatable cylinder mounted over the bed and movable toward and from the same, a belt connection between the shaft and the cylinder, a crank member constituting a part of the driving mechanism, a rock shaft having cams, connections between the cams and the cylinder, and a link connection between the rock shaft and the crank member of the driving mechanism.
17. In a printing press, the combination with a roller-supported bed, of means for reciprocating the same, a cylinder movable toward and from the bed, and means for thus moving the cylinder, said means including cams connected to the cylinder, and detachable connections between the bed-operating means and the cams for moving the latter.
18. In a printing press, the combination with a frame, of a feed table mounted thereon, a reciprocating bed mounted on the frame and movable beneath the table, a cylinder journaled at one end of the table and located over the bed, driving mechanism for reciprocating the bed, said mechanism having a belt connection with the cylinder for continuously rotating the same in one direction, upper and lower coacting tapes located beneath the table and above the bed, the upper of said tapes passing around the cylinder, and a driving pulley for the lower of said tapes, said pulley engaging the belt connection with the cylinder.
19. In a printing press, the combination with a frame, of a reciprocating bed mounted thereon, cylinder co-operating with the bed and movable toward and from the same, driving mechanism for reciprocating the bed, a belt connection between the driving mechanism and cylinder, coacting tapes, certain of which are operated from the cylinder, and means operated by the cylinder-driving belt for moving the other tapes.
20. In a printing press, the combination with a supporting frame, of a reciprocating bed mounted on the frame,

- driving mechanism including means for reciprocating the bed, a rotary cylinder coacting with the bed and movable toward and from the same, means operated by the driving mechanism for continuously rotating the cylinder and effecting its movement toward and from the bed, delivery tapes driven from the cylinder and the means for rotating said cylinder, a fly frame receiving the paper from the tapes, means connecting the fly frame and the driving mechanism, a paper clamping device, and gages movable into and out of coaction with the cylinder, common means connected with the driving mechanism for simultaneously operating the gages and clamping device in opposite directions,inking mechanism including a fountain feed roll, a distributing roll, and a transmitting roll operating between the feed roll and distributing roll, and a connection between the transmitting roll and the clamping device. 5
21. In a printing press, the combination with a bed, of a cylinder movable into and out of coaction therewith, driving mechanism for operating the bed, and connections between the driving mechanism and cylinder for rotating the latter, said connections including a clutch comprising constantly associated elements connected respectively to the driving mechanism and cylinder, said elements having an automatic interlocking connection that at all times permits the element connected to the cylinder to operate at a greater speed than the element connected to the driving mechanism and automatically connects the elements whenever the speed of the driving mechanism exceeds that of the cylinder. 10
22. In a printing press, the combination with a bed, of a cylinder movable into and out of coaction therewith, driving mechanism for operating the bed, and connections between the driving mechanism and cylinder for rotating the latter, said connections including a clutch comprising relatively rotatable elements connected respectively to the driving mechanism and cylinder, said elements having an interlocking connection that at all times permits the element connected to the cylinder to rotate at a greater speed than the element connected to the driving mechanism, and at all times prevents the rotation of the element connected to the driving mechanism at a greater speed than the element connected to the cylinder. 15
23. In a printing press, the combination with a bed, of a cylinder movable into and out of coaction therewith, driving mechanism for operating the bed, and connections between the driving mechanism and cylinder for rotating the latter, said connections including a clutch comprising relatively rotatable elements that are connected respectively to the driving mechanism and cylinder, and a device carried by one element and detachably interlocking with the other element, said device being automatically moved out of its interlocking engagement by the element that it engages, upon a predetermined change in the relative speeds of the clutch elements. 20
24. In a printing press, the combination with a bed, of a cylinder movable into and out of coaction therewith, driving mechanism for operating the bed, and connections between the driving mechanism and cylinder for rotating the latter, said connections including a clutch comprising relatively rotatable elements connected respectively to the driving mechanism and cylinder, one of said elements having a recess provided with a sharp shoulder, and an inclined shoulder, and a device carried by the other element and detachably engaging in the recess, said device being moved out of the recess by the inclined shoulder thereof when the speed of the cylinder is greater than that of the driving mechanism. 25
25. In a printing press, the combination with a cylinder, of a bed movable into and out of engagement with the cylinder, said cylinder being operated by the bed when in engagement with the same, operating means for effecting the rotation of the cylinder when the same is out of engagement with the bed, a portion of said operating means being driven by the cylinder when the latter is in engagement with the bed, and paper delivery mechanism including coacting devices, one of which is driven by the cylinder the other device being driven by said portion of the operating means. 30
26. In a printing press, the combination with a cylinder, of a bed movable into and out of engagement with the cylinder, said cylinder being operated by the bed when the two are in engagement, driving mechanism, means for rotating the cylinder when the same is out of engagement with the bed, said means having a clutch connection with the driving mechanism, and coacting paper delivering tapes, one of which is driven by the cylinder, the other being operated by and having an engagement with said means for rotating the cylinder. 35
27. In a printing press, the combination with a bed, of a cylinder movable toward and from the same, means for thus moving the cylinder, said means including a movable actuating element, a movable actuated element having connections with the cylinder and having a portion normally located in the path of movement of the actuating element, said elements being relatively movable to place 90 said portion of the actuated element out of said path of movement of the actuating element, and means for yieldingly maintaining the elements with said portion in said path of movement. 95
28. In a printing press, the combination with a bed, of a cylinder movable toward and from the same, means for thus moving the cylinder, said means including a rotating actuating element, a reciprocatory actuated element having connections with the cylinder and having a portion in the path of movement of the actuating element, said elements being relatively movable to place said portion out of the path of movement of the actuating element, and a spring for yieldingly maintaining the elements with said portion in said path of movement. 100
29. In a printing press, the combination with a bed, of a cylinder movable toward and from the same, and means for thus moving the cylinder, said means including a rotatable shaft having a crank device, a reciprocatory link having a head slidable upon the shaft and movable toward the same, said head having devices disposed in the path of movement of the crank device, and a spring bearing against the head for yieldingly urging the same toward the crank device. 110
30. In a printing press, the combination with a bed and rotating cylinder, of means for operating the bed, said bed having an engagement with the cylinder to drive the same, operating means for rotating the cylinder when the latter is out of driven engagement with the bed, said operating means including an element actuated by the bed-operating means, an element operating the cylinder during a portion of its movement and operated by said cylinder during another portion of the movement of the cylinder, a clutch connection between the elements to permit the independent movements of the cylinder-operated element, and delivery mechanism operated by said cylinder-operated element. 115
31. In a printing press, the combination with a bed and rotating cylinder, of means for moving the bed, said bed having an engagement with the cylinder to drive the same, operating means for rotating the cylinder when the latter is out of driven engagement with the bed, said operating means including a shaft, a belt pulley having a clutch engagement with the shaft, and a belt connecting the pulley and cylinder, and tapes driven by the belt. 120
- In testimony, that I claim the foregoing as my own, I have hereto affixed my signature in the presence of two witnesses.

BENJAMIN W. MORGAN.

Witnesses:

J. M. THOMAS,
H. H. THOMAS.

It is hereby certified that in Letters Patent No. 858,743, granted July 2, 1907, upon the application of Benjamin W. Morgan, of Atlanta, Georgia, for an improvement in "Printing-Presses," an error appears in the printed specification requiring correction, as follows: In line 68, page 4, the word "members" should read *member*; and that the said Letters Patent should be read with this correction therein that the same may conform to the record of the case in the Patent Office.

Signed and sealed this 30th day of July, A. D., 1907.

[SEAL.]

C. C. BILLINGS,
Acting Commissioner of Patents.
